UNITED STATES PATENT OFFICE.

PATRICK SCANLIN, OF BOONE, IOWA.

BUMPING-POST.

SPECIFICATION forming part of Letters Patent No. 683,502, dated October 1, 1901.

Application filed March 11, 1901. Serial No. 50,602. (No model.)

To all whom it may concern:

Be it known that I, PATRICK SCANLIN, a citizen of the United States, residing at Boone, in the county of Boone and State of Iowa, 5 have invented certain new and useful Improvements in Railway Bumping-Posts, of which the following is a specification.

The object of my invention is to provide a bumping-post of simple, durable, and inexpensive construction in which a maximum 10 of strength is obtained through the use of a minimum amount of material.

A further object is to provide a device of 15 this class in which the braces for the bumping-post are in the rear of the post and connected with the track-rails, so that all of the strain upon a post will be borne by the track-rails upon which the car or cars to be stopped by the bumper are resting.

20 A further object is to provide a device of this class in which the track-rails are not bent or their construction changed in any manner whatever for adapting them for use in connection with my improved bumping-post. 25 Hence my improvement may be applied as an attachment to a track at any point throughout its length and may be removed without injuring or in any way affecting the track-rail.

30 My invention consists in certain details in the construction, arrangement, and combination of the various parts of the device whereby the objects contemplated are attained, as hereinafter more fully set forth, pointed out in my claims, and illustrated in the accompanying drawings, in which—

35 Figure 1 shows a side elevation of the device applied to a track. Fig. 2 shows a top or plan view of the same, and Fig. 3 shows an end elevation of same.

40 Referring to the accompanying drawings, I have used the reference-numeral 10 to indicate the parallel track-rails of ordinary form, secured to the ties 11. These track-rails are connected by means of the tie-rods 12 of ordinary construction. At a point midway between the track-rails and between the two ties I have placed an upright post 13 to project some distance above the track and having 45 its lower end anchored in any suitable manner in the ground. On the front and rear faces of the upper end portion of the posts I

have placed the metal posts 14. The upright post is braced by means of two rail-sections shaped as follows: Each of said rail-sections is provided with a part 15 to lie parallel with 55 the track-rail. This part is preferably connected with the track-rail by means of bolts 16, passed through the track-rail and said part 15, and a filler-block 17 is placed between these adjacent portions of the rails. A part 60 18 of the brace-rails extends inwardly and upwardly to the rear plate 14, and then a part 19 extends straight upwardly. The parts 19 of the two braces are brought together and extend in parallel planes in a vertical direction. 65 A filler-block 20 is placed between them and the bolts 21, firmly connecting their ends together. A metal strap 22 has its ends secured by bolts 23 to the outer surfaces of the track-rails some distance in advance of the post 13, 70 and its central portion passes in the rear of the post 13 and engages the rear surfaces of the parts 19 of the braces. I have provided means whereby the said metal strap, together with the upwardly-projecting portions of the brace-rails, is firmly and immovably secured to the post, as follows: A U-bolt 24 has its central portion passed over the rear end of the strap 22 and its ends passed through the block 20 and through the plates 14 and post 13. The 80 nuts 25 on the forward ends of the U-bolt may be adjusted to firmly clamp all of said parts in position.

I have provided a yielding buffer to project from the front surface of the post, which 85 buffer is constructed as follows: The body portion 26 is passed through the post and through the strap 22, and a nut 27 is provided on its rear end. An enlarged head or buffer plate 28 is fixed on the front end thereof, and 90 a spring 29 is interposed between the said head 28 and the plate 14. This buffer is located at such distance from the track as to engage the buffer of an ordinary railway-car. Obviously its position may be changed to correspond with cars having buffers at various 95 distances from the track, or two or more buffers at different heights may be used. At the rear end of the brace-rails I have provided a bar 30, the ends of which are clamped to the 100 track-rails in such position that the forward edge of the bar 30 will engage the rear ends

of the brace-rails to thereby prevent longitudinal movement of the brace-rails relative to the track-rails.

In practical use it is obvious that my improved bumping-post may be attached to any ordinary railway-track, either at the end of the track or at any point throughout the length thereof, without in any way altering the track-rails. Assuming the device to be applied to a railway-track, it is obvious that the impact from a car striking the post will be resisted by the brace-rails, and these rails are firmly secured at their rear ends to the same track-rails upon which the car or cars are standing, so that substantially all the force of a shock to the bumping-post will be directly applied to the track-rails. The strap 22 is provided for the purpose of resisting such strains upon the brace-rails as would tend to bend the brace-rails upwardly, and as the strain in this direction would not be great the said strap need not be of great strength, and hence not cumbersome or heavy. It is obvious, further, that by using the brace-rails in the manner shown the function of the upright post is only to support the bumper and to connect the various parts with each other. Hence it is not necessary that a large or heavy post be utilized. It is to be noted, further, in this connection that all of the parts of the bumping-post are made of materials that can readily, quickly, and easily be obtained by the ordinary railway repairman and that none of said parts need be formed or made on specially-designed machinery.

Having thus described my invention, what I claim, and desire to secure by Letters Patent of the United States therefor, is—

1. An improved railway bumping - post, comprising in combination, an upright post to be arranged between the track-rails, two braces having their forward end portions in engagement with the post and their rear end portions inclined downwardly and outwardly and in engagement with the track-rails, means for clamping said rear ends of the braces to

the track-rails and a metal strap secured to the track-rails in front of the post and passed around the rear of the post and overlapping the front end portions of said braces, for the purposes stated.

2. An improved railway bumping - post, comprising in combination, two track-rails, an upright between the rails, two braces having their rear ends clamped to the track-rails, their central portions extended inwardly, upwardly, and forwardly, and their forward ends extended parallel with each other, a metal strap having its ends secured to the track-rails in front of the post and its central portion passed in the rear of and in engagement with the forward end of the said braces, means for clamping said strap and braces to the post, and a yielding bar mounted on the forward face of the post, all arranged and combined substantially in the manner set forth, and for the purposes stated.

3. An improved railway bumping - post, comprising in combination, two track-rails, an upright between the rails, two braces having their rear ends clamped to the track-rails, their central portions extended inwardly, upwardly, and forwardly, and their forward ends extended parallel with each other, a metal strap having its ends secured to the track-rails in front of the post and its central portion passed in the rear of and in engagement with the forward end of the said braces, means for clamping said strap and braces to the post, and a yielding bar mounted on the forward face of the post, all arranged and combined substantially in the manner set forth, and for the purposes stated.

PATRICK SCANLIN.
